US0D1029395S

(12) **United States Design Patent** (10) **Patent No.:** **US D1,029,395 S**
(45) **Date of Patent:** **** May 28, 2024**

(54) **PORTABLE ELECTRIC NAIL DRILL**

(71) Applicant: **Dongguan Selerwin Innovation Technology Co., Ltd**, Dongguan (CN)

(72) Inventor: **Shan Qin**, Dongguan (CN)

(**) Term: **15 Years**

(21) Appl. No.: **29/885,732**

(22) Filed: **Feb. 28, 2023**

(30) **Foreign Application Priority Data**

Nov. 1, 2022 (CN) 202230725816.6

(51) **LOC (14) Cl.** **28-03**

(52) **U.S. Cl.** **D28/58**
USPC .....

(57) **CLAIM**

The ornamental design for a portable electric nail drill, as shown and described.

DESCRIPTION

FIG. 1 is a perspective view of a portable electric nail drill showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged top plan view thereof;

FIG. 10 is an enlarged bottom plan view thereof;

FIG. 11 is an enlarged view of portion 11 shown in FIG. 1; and,

FIG. 12 is an enlarged view of portion 12 shown in FIG. 1. The dash-dash broken lines in the drawings depict portions of the portable electric nail drill that form no part of the claimed design.

The dot-dash broken lines represent boundaries of the enlarged portions and form no part of the claimed design.

1 Claim, 12 Drawing Sheets
